CARRYING CASE FOR FISHING POLES OR THE LIKE

John Michal, Box 7, South Prairie, Wash. 98385

Filed Aug. 23, 1974, Ser. No. 500,101

Term of patent 14 years

Int. Cl. D3—02

U.S. Cl. D87—1 R

FIG. 1 is an end view of a carrying case for fishing poles or the like showing my new design;

FIG. 2 is a perspective view thereof;

FIG. 3 is an elevational view of the end opposite that shown in FIG. 1;

FIG. 4 is a top plan view shown broken away for convenience of illustration;

FIG. 5 is a side elevational view thereof; and
FIG. 6 is a bottom plan view.

I claim:

The ornamental design for a carrying case for fishing poles or the like, as shown.
